UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

PAPER-FEED MECHANISM.

Application filed July 17, 1920. Serial No. 396,888.

To all whom it may concern:

Be it known that I, OTTO A. HOKANSON, a citizen of the United States, residing at Woodstock, in the county of McHenry and 5 State of Illinois, have invented certain new and useful Improvements in Paper-Feed Mechanism, of which the following is a specification.

This invention relates generally to typewriters, and more specifically to the paper platen and the mechanism connected therewith by which the paper is held and guided about the platen so that it will be fed relative thereto when the platen is rotated.

15 The invention has for its object the provision of mechanism of the class named which shall be of improved construction and operation. It is exemplified in the combination and arrangement of parts shown 20 in the accompanying drawings and described in the following specification, and it is more particularly pointed out in the appended claims.

In the drawings—

25 Fig. 1 is a fragmentary front elevation of a portion of a typewriter platen carriage showing one embodiment of the present invention applied thereto;

Fig. 2 is a top plan view of the mechanism shown in Fig. 1, with parts omitted; and

Fig. 3 is an end elevation of the mechanism shown in Fig. 1, with parts in section.

Although the invention is applicable to 35 various forms of typewriters, the embodiment of the invention illustrated in the drawings is represented as being applied to a typewriter having a folding support for the platen carriage arranged to permit 40 the typewriter parts to be folded into compact relation.

A portion of the main frame of a typewriter is shown in Fig. 3 and designated by the numeral 10 on which a pair of arms 11 are pivoted at 12. A platen carriage frame 13 is mounted on the ends of the arms 11 and may be swung from the position shown in Fig. 3 about the pivot 12 to a folded or inoperative position. A platen carriage 14 is mounted on the carriage frame 13 and is provided with ball bearings 15 to facilitate the movement of the carriage on its frame. At each end of the carriage 14 are brackets or end plates 16 and 17 arranged in upright 55 position for supporting a platen 18 which is

provided with a spindle or shaft 19 journaled to rotate in the brackets 16 and 17. The bracket 16 is bored to receive one end of the spindle 19, and the bracket 17 is provided with an open notch 20 carrying a sleeve 21 which forms a bushing for the end of the spindle 19 supported by the bracket 17. The sleeve 21 is provided with flanges 22 and 23 and a tubular extension 24, the end of which bears against a collar 25 secured to the platen shaft adjacent the end of the platen 18. The flange 23 bears against the inner face of the end plate 17, and the flange 22 is spaced outwardly from the outer face of the end plate 17 and engages the inner end of the platen knob 26 secured to the extended end of the platen shaft 19. The sleeve 21 is held in position in the opening 20 by a hook 27 pivoted at 28 on the end plate 17 and provided with a finger-piece 29 by which it may be swung forwardly to release the sleeve 21. When the hook 27 is disengaged from the sleeve the end of the platen may be lifted until it clears the end plate 17, after which the opposite end of the platen shaft may be withdrawn from the bearing in the end plate 16, and thus the platen may be easily removed 70 from its support in the platen carriage. The hook 27 is formed to provide a seat 30 having the same radius as the outer periphery of the sleeve 21 so that the hook will snap into place on the top of the sleeve and will not be accidentally disengaged. A depression 30' is provided in the end plate 17 and a knob is formed on the inner face of the hook 27 for engaging the depression 30' to retain the hook in position when disengaged from the sleeve 21.

Two sets of feed rollers 31 and 32 are arranged to bear against the periphery of the platen 18 and hold the paper against the surface of the platen so that when the platen is rotated the paper will be fed about its periphery. The roller 31 is mounted on a spindle 33, and the rollers 32 are carried by a spindle 34. The spindles 33 and 34 are journaled in opposite ends of rocker arms 35 which are pivoted on a bar or rod 36. A paper deflector or guide 37 of sheet material is provided with downwardly bent ears 38 which are pivoted on the rod 36 adjacent the rocker arms 35, the ears being provided with bifurcations 39 which are slightly closed at their outer ends so that 80 85 90 95 100 105 110

they will snap over the bar 36 and thus be retained in position. In Fig. 2 the ears 38 are shown in section with the deflector 37 removed; but the position and outline of the deflector in this figure are indicated by broken lines. It will be seen that the deflector 37 is provided with cut-away portions to permit the rollers 31 and 32 to project above the deflector and engage the periphery of the platen. The edges of the deflector adjacent the rollers are bent downwardly, as shown at 40, to prevent the edge of the paper from catching on the edge of the deflector plate.

15 The bar 36 is supported by links 41 and 42 at opposite ends of the platen carriage, which links are pivotally mounted on the carriage end plates by bolts 43 and 44, respectively. The links 41 and 42 are each 20 provided with a downwardly extending bracket 45, and the brackets 45 are connected by a bar 46 extending transversely of the typewriter and secured to its supporting brackets by screws 47. Each of the 25 brackets 45 carries a downwardly bent flange 48 having a knob 49 punched rearwardly thereon which engages one end of a coil spring 50. The opposite end of the 30 spring 50 is supported by an adjustable screw 51 having a lock nut 52. The spring 50 presses forwardly on the flanges 48 of the brackets 45 so that the links 41 are forced upwardly to hold the rollers 31 and 32 resiliently against the periphery of the 35 platen 18. The amount of pressure between the rollers and platen is regulated by the adjustment screw 51. The link 41 is provided with an upwardly extending lever arm 53 by which the bar 46 and the brackets 45 may 40 be swung rearwardly against the force of the spring 50 to release the paper from the pressure of the rollers 31 and 32. The lever arm 53 is provided with a lug 54 which cooperates with a projection 55 on the plate 45 17 to hold the arm forwardly to retain the rollers 31 and 32 in their released position. The lug 54 may be readily swung past the 50 projection 55 by a slight lateral movement of the lever arm 53.

55 For retaining the upper edge of the paper in position against the platen above the printing line a paper bail or bar 56 extends longitudinally of the carriage and is supported on arms 57 pivoted at 58 on the end plates 16 and 17. A spring 59 is secured to each arm 57 and to the platen carriage end plates to hold the bar 56 in resilient engagement with the platen. If the bar 56 is drawn forwardly until the axis of the spring 60 59 passes the pivotal center 58 the bar will be retained in its forward position, and stops 60 are provided on the carriage end plates to limit the forward movement of the bar. A supplemental paper guide 61 is supported at 62 on the carriage 14 in position to di-

rect the upper edge of the paper along a plane lying between the bar 56 and the platen when the bar is in its forward or inactive position. When it is desired to place a sheet of paper in the machine the paper 70 bail, including the bar 56 and supporting arms 57, is swung forwardly and the paper inserted between the guide 37 and the platen. Rotation of the platen will automatically feed the forward edge of the paper between 75 the paper bail and the surface of the platen without the necessity of any manipulation of the paper on the part of the operator to guide it beneath the paper bail. After the paper has been thus moved to position a 80 touch on the paper bail will return it to its operative position so that the paper will be held against the surface of the platen. The supplemental paper guide 61 may be provided with reinforcing spring fingers 63 secured 85 to the platen carriage 14 at spaced intervals along its front edge.

A paper table 64 is pivotally supported at 65 at the rear of the platen and is provided with a spring 66 and a stop 67 for holding it in position to direct a sheet of paper to the feed roller 31. The paper table 64 may be easily swung forwardly to permit the operator to see the mechanism at the back of the typewriter frame when desired. 95

I claim:—

1. In a typewriter, a platen support having spaced end plates, a platen journaled between said end plates, a bracket pivotally mounted on each of said end plates, a pivot rod extending longitudinally of said platen and supported by said brackets, rocker arms mounted on said pivot rod and having rollers carried therebetween at opposite ends thereof and arranged to engage the periphery of said platen, a paper guide plate pivoted on said rod and bridging the space between said rollers to guide a sheet of paper from one of said rollers to the other, and resilient means for exerting pressure on said brackets to yieldingly hold said rollers against the periphery of said platen. 100

2. In a typewriter, a platen support having a platen journaled therein, a pivot rod extending longitudinally of said platen and having rocker arms pivotally mounted in spaced relation thereon, rollers journaled in spaced relation on said rocker arms and arranged to engage the periphery of said platen, and a paper guide plate for directing a sheet of paper from one of said rollers to the other, said guide plate having bifurcated projections arranged to resiliently snap over said pivot rod to pivotally support said paper guide plate. 110

3. In a typewriter, a platen support having a pair of spaced end plates, a platen journaled between said end plates, a bracket pivotally mounted on each of said end plates, means for connecting said brackets 130

to hold them against angular displacement relative to one another upon their pivotal supports, paper feed rollers supported by said brackets for engaging said platen, 5 silent means for exerting pressure on said brackets to hold said paper feed rollers against said platen, and means for swinging said brackets about their pivotal supports to release said paper feed rollers from 10 said platen.

4. In a typewriter, a platen support comprising spaced end plates, a platen journaled between said end plates, paper feed rollers for engaging said platen to hold a sheet of 15 paper in position against the periphery thereof, a support for said rollers comprising a bracket pivotally mounted on one of said end plates and having a supporting arm for said rollers, a lever arm for swinging said bracket about its pivotal support, an adjustable spring cooperating with said bracket to hold said rollers against said platen, and means for retaining said lever arm in position to hold said rollers out of 20 engagement with said platen.

5. In a typewriter, a platen support having a pair of spaced end plates, a platen journaled between said end plates, a bracket pivotally mounted on each of said end 30 plates, means for connecting said brackets to hold them in fixed angular position relative to one another, supporting arms connected with said brackets, a pivot rod connecting said supporting arms, rocker bars 35 pivotally mounted on said rod in spaced relation relative to one another, rollers journaled on said rocker bars and opposite sides of said pivot rod and arranged to engage the periphery of said platen, a paper guide 40 plate pivotally mounted on said pivot rod and forming a bridge between said rollers for directing a sheet of paper from one to the other thereof, springs connected with said brackets for holding said rollers against 45 said platen, and a lever connected with one of said brackets for releasing said rollers from said platen.

6. In a typewriter, a platen carriage having a platen journaled therein, a paper-holding bail pivoted on said platen carriage and arranged to engage a sheet of paper to hold 50 said paper against the periphery of said platen, said bail being arranged to swing forwardly about its pivot and out of contact with said platen to permit insertion of paper between said bar and platen, and a spring 55 connected with said bail and arranged to be moved by said bail past a central position so that said spring will retain said bail in either its operative or inoperative position.

7. In a typewriter, a platen carriage having spaced end plates, a platen journaled between said end plates, a paper-holding bail having supporting arms pivotally mounted 60 on said end plates and having a paper-

retaining bar extending longitudinally of said platen, said bar being movable forward away from said platen into an inoperative position to permit insertion of paper between said bar and platen, a stop for limiting the movement of said bar away from said platen, and a spring connected with said bail and with one of said supporting plates at points on opposite sides of the pivotal support for said bail so that the longitudinal axis of said spring will move past the pivotal support of said bar as said bail is swung into and out of operating position. 70

8. In a typewriter, a platen carriage frame having spaced supports, a platen journaled between said supports, a paper-retaining bail comprising upright arms pivoted on said supports, a bar extending longitudinally of said platen and supported by said arms, said bar having a flat surface arranged to direct 80 sheets of paper against said platen and to engage said platen at one edge of said bar, and resilient means for holding said bar against said platen. 85

9. In a typewriter, a platen support, a platen journaled therein, a plurality of paper feed rollers, means for resiliently pressing said rollers against said platen, a paper guide for directing a sheet of paper from one of said rollers to another, a supplemental paper guide for directing the paper after it leaves said rollers, and a paper holder carried by said support and movable into a position away from said platen in which the paper is directed by said supplemental guide between said holder and platen. 95

10. A typewriter comprising a platen holder, a platen journaled in said holder, a pair of spaced rollers arranged to bear against the periphery of said platen, a paper table for directing a sheet of paper between said platen and one of said rollers, a paper guide arranged to bridge the space between said rollers and direct said sheet of paper from one of said rollers to the other, a supplemental paper guide for directing said paper away from said last-mentioned roller, and a paper bail pivotally mounted on said platen holder and comprising a bar extending longitudinally of said platen and movable into one position to receive the paper from said last-mentioned guide and into a second position for holding said paper against said platen. 105

11. In a typewriter, a platen carriage, a platen journaled in said carriage, a paper guide plate secured to said carriage adjacent one edge thereof and having an edge portion arranged adjacent said platen, and supplemental spring fingers arranged to engage 110 said guide plate to press said guide plate toward said platen. 120

12. A typewriter comprising a main frame and a supplemental frame pivotally mounted thereon, a platen carriage supported by 130

- 5 said supplemental frame and movable therewith into and out of operating position, paper feed mechanism mounted on said platen carriage and movable with said supplemental frame, said feed mechanism comprising spaced rollers arranged to bear against said platen, guide plates cooperating with said rollers to direct a sheet of paper about said platen and between said 10 platen and said rollers, and a paper-holding device for retaining said sheet against the face of said platen at the printing line of said typewriter.
13. A typewriter comprising a main frame, 15 arms pivoted on said frame, a platen carriage support mounted on said arms, a platen carriage arranged to move along said support, a platen journaled in said carriage, paper feed mechanism for said platen comprising rollers for resiliently pressing a sheet of paper against said platen, guide plates for directing said sheet about said platen, and a paper bail pivotally mounted on said carriage and movable into and out 20 of position to hold said sheet against the surface of said platen.
14. A typewriter comprising a main frame, 25 a supplemental frame mounted on said main
- frame, a platen carriage supported by said supplemental frame and movable therewith into and out of operating position, said carriage being inverted when in its inoperative position, a platen journaled in said carriage and having a bearing with an open upper portion for supporting one end thereof, and means for closing the open portion of said bearing to retain said platen in place therein when said carriage is inverted.
15. In combination, a typewriter having a platen carriage thereon and movable into and out of operating position, said carriage being inverted when in its inoperative position, spaced upright plates on said carriage, a platen supported by said carriage and having a platen shaft journaled in said plates, one of said plates having a bearing for said shaft with the upper portion thereof open, and a retainer pivoted on said plate and movable into and out of position to close said opening and retain said shaft in said bearing when said carriage is inverted.

In testimony whereof I have signed my name to this specification on this 28th day of June, A. D. 1920.

OTTO A. HOKANSON.
